Primary Examiner — Jae LiangCLAIM

We claim the ornamental design for a glass, as shown and described.

DESCRIPTION

FIG. 1 is a side elevational view of a glass showing our new design; with the other side view being identical;
 FIG. 2 is a bottom elevational view thereof;
 FIG. 3 is a top elevational view thereof;
 FIG. 4 is a front top perspective view thereof; and,
 FIG. 5 is a front bottom perspective view thereof.
